UNITED STATES PATENT OFFICE.

CHARLES HARRY COBB, OF BUTTE, MONTANA.

RADIATOR SUPPORT.

Application filed April 11, 1922. Serial No. 551,486.

To all whom it may concern:

Be it known that CHARLES HARRY COBB, a citizen of the United States of America, residing at Butte, in the county of Silver Bow and State of Montana, has invented new and useful Improvements in Radiator Supports, of which the following is a specification.

The object of the invention is to provide a supporting means for radiators which shall be concealed from view and while facilitating the mounting of the radiator and the adaptation of the radiator thereto, shall support the weight of the latter entirely from the wall under conditions which do not involve applying a shearing strain to anchor bolts or the equivalents thereof by which attachment may be made to the wall, and which therefore are not subject to injury, displacement or failure regardless of the weight of the radiator; and furthermore to provide a supporting means whereby the radiator is held in spaced relation both with the floor and the wall to permit of cleaning, laying the floor after the radiators are in place, laying and removing carpet or rugs and of disposing the radiator at any desired elevation to accommodate special or unusual heights of base boards; and with these objects in view the invention consists in a construction and combination of parts of which a preferred embodiment is shown in the accompanying drawings, wherein:—

Figure 1 is a front view of a radiator supported by means constructed in accordance with the invention.

Figure 2 is a side view of the same.

Figures 3 and 4 are plan views respectively of the upper and lower members of the support.

The support contemplates upper and lower members of which the former indicated at 10 serve merely as a spacing or distance member to position the radiator indicated at 11 while the latter indicated generally at 12 is designed to bear the weight of the radiator. In the application of the support in preparation for the attachment thereto of the radiator it is proposed to provide for positioning the anchoring means during the roofing or building operations as for example the construction of a wall upon which the radiator is to be suspended, so that after the wall has been completed and finished the radiator may be put in place either before or after the flooring has been completed, and

to this end there is employed in connection with each of the supporting members an anchor bolt engaged with the wall structure whether of tile, brick or other material 60 adapted to be set during the construction of the wall or erection of the masonry portion of the wall. In the construction illustrated the anchor bolt 13 for the upper supporting member is arranged to project beyond the surface of the finished wall a sufficient distance to receive a nut 14 by which a spacing bracket 15 is secured against the surface of the wall, said bracket preferably consisting of a horizontal member 65 of a length determining the distance between the rear surface of the radiator and the plane of the wall and terminal downwardly and upwardly extending ears 16 and 17, of which the former is engaged by the anchor bolt 13 and the latter is engaged by a retaining bolt 18. In order to provide for an adjustment of the bracket relative to the anchor bolt, so that mathematical accuracy in the setting of the anchor bolt may 70 not be required (and which may be prevented by the fact that the joints between the bricks or tiles may not occur in the right place to suit the anchor bolt), the depending ear 16 of the bracket is provided 75 with a transverse slot 16^a for the reception of the anchor bolt.

The retaining bolt engages a vertical slot 17^a in the upwardly directed ear 17 of the bracket, said slot being open ended to facilitate the engagement of the retaining bolt therewith, and the ear being provided with lugs 19 forming a seat for the reception of the nut 20 of the retaining bolt, so as to hold the nut against turning during the 95 tightening of the retaining bolt. Fitted to the head of the retaining bolt is a cupped bearing plate 21 of conical form to snugly seat between the coils of the radiator.

In connection with the anchor bolt 22 of the lower supporting member there is employed an anchor plate 23 which is preferably arranged against the rough wall surface so as to be covered by the wall finishing material such as the plaster shown at 24, to afford a means of concealing the anchor plate, and at the lower end of the anchor plate there is arranged a foot 25 extending into the wall structure and serving as the actual active element for supporting the weight which is to be imposed upon the lower supporting member when the radi-

ator is positioned. Extending outwardly from the anchor plate is a supporting eye 26 for engagement by an anchor bolt 27 which supports a stirrup 28 having a forwardly or outwardly projecting hook 29 upon which the lower circulating tube 30 of the radiator rests. The hook extends between the coils of the radiator for engagement with the said tube or coupling.

10 The eye 26 from which the anchor bolt depends is provided with a transverse slot 26^a to permit of adjustment of the hanger bolt and hence of the stirrup laterally to suit the intervals between the coils and at 15 the same time permit of the arrangement of the radiator in the desired position longitudinally with relation to the wall adjacent to which it is disposed. The eye 26 is provided at its upper side with a pair of 20 lugs 31 forming a seat for the reception of the nut 32 which engages the end of the hanger bolt so that the latter may be turned by means of a wrench applied to the head 33 bearing against the lower side of the stirrup 25 to adjust the radiator vertically and hence 25 to the desired distance above the plane of the floor. Furthermore the rear or inner side of the stirrup is provided with a bearing face 34 for direct contact with the surface of the wall and this bearing occurs adjacent to and preferably opposite the lower 30 end of the anchor plate from which projects the foot 25, as shown in the drawing, so that the weight applied to the stirrup by the radiator is applied perpendicularly to the surface of the wall through the bearing face 34 and the weight applied by the stirrup to the hanger eye 26 is supported directly by the foot of the anchor plate.

40 Hence there is no shearing strain applied to either of the anchor bolts and the upper anchor bolt serves merely as a means of holding the radiator in a vertical position so that its weight may be carried by the lower member of the support, and the application or hanging of the radiator may occur after the finishing of the wall has been completed and under such conditions as to permit of cleaning beneath and in rear thereof or laying and removing carpets or other floor covering without involving any inconvenience.

Having described the invention, what is claimed as new and useful is:—

1. A support for radiators comprising an anchor plate adapted for arrangement against a rough wall surface so as to be covered by the finishing material thereof, said anchor plate being provided at its lower end with a right angularly disposed foot extending into the wall structure and serving as a prime supporting element to resist downward strain, anchoring means for securing the anchor plate at the upper end to resist strains tending to pull the plate from the wall surface, a stirrup adapted for engagement with the lower portion of a radiator, the anchor plate being provided with a supporting element protruding beyond the finished wall surface, an anchor bolt carried by said supporting element and depending therefrom and paralleling the wall surface and engaging the stirrup, an anchor nut applied to the bolt, and means operatively connecting the nut with said element to prevent displacement of the nut, said stirrup being provided with a bearing foot for contact with the outer wall surface in a position overlying said first named foot to resist any outward displacement of the latter foot, said supporting element provided with a transverse slot, the long dimension of which being parallel with the wall surface with the anchor bolt passing through said slot for transverse adjustment.

2. As an article of manufacture, an anchor plate adapted for arrangement against a rough wall surface so as to be covered by the finishing material thereof in conjunction with a support for the upper part of the radiator, said anchor plate comprising a body having a vertical slot at its upper end to receive securing means to penetrate a wall and provided at its lower end with a right angularly disposed foot extending into the wall adapted as a prime support to resist downward strain of a radiator, the body of the anchor plate having an outstanding lug with a transverse elongated slot to receive attaching means for a support for the lower part of the radiator, said last named support adapted to overlie the footed portion of the anchor plate to resist any outward displacement thereof.

In testimony whereof he affixes his signature.

CHARLES HARRY COBB.
